UNITED STATES PATENT OFFICE.

AUSTIN F. JACKSON, OF TAUNTON, MASSACHUSETTS.

DESIGN FOR A SPOON.

SPECIFICATION forming part of Design No. 21,135, dated October 27, 1891.

Application filed September 22, 1891. Serial No. 406,533. Term of patent 7 years.

To all whom it may concern:

Be it known that I, AUSTIN F. JACKSON, a citizen of the United States, residing at Taunton, in the county of Bristol, and State of Massachusetts, have invented and produced a new and original Design for Handles of Spoons, Knives, Forks, &c., of which the following is a specification, reference being had to the accompanying drawing, forming part thereof.

10 The figure is an upper or face view of my design applied to a coffee-spoon.

The leading feature of my design is a representation of a pansy-blossom *a*, arranged at the end of the handle. Below the blossom 15 are disposed a bunch of shoots or leaves *b*, rising from a band *c*, and between the band *c*

and another *c'*, near the bowl, the shank is ornamented with a twisted or roped configuration.

What I claim is—

20 The design for the handles of spoons, knives, forks, &c., consisting of the representation of a pansy-blossom *a*, arranged at the extreme end of the handle, the shoots and leaves *b*, and the two ornamental bands *c c'*, with 25 twisted or roped shank between, substantially as shown and described.

AUSTIN F. JACKSON.
